NOISE SHIELD FOR HANDSETS

Paul S. Veneklasen, South Pasadena, Calif., assignor to the United States of America as represented by the Executive Secretary of the Office of Scientific Research and Development

Application January 29, 1946, Serial No. 644,008

5 Claims. (Cl. 179—188)

1

This invention relates to telephone handsets. More particularly, the invention is concerned with a telephone handset which includes a noise shield member adapted to be mounted adjacent to the transmitter end of the handset. The present invention is an improvement over a noise shield described by me in a copending application, Serial No. 574,367, filed Jan. 24, 1945, executed by me December 15, 1944, entitled "Hand telephone sets," issued U. S. Patent No. 2,456,346, Dec. 14, 1948.

An object of the invention is to improve the operation of telephone handsets and to devise a noise shield member for excluding ambient noise during the operation of a handset. Another object of the invention is to provide a noise shield member which is so constructed as to permit substantially sealed engagement of this member over the face of the user and to maintaining this sealed relation during speech. Other objects and novel features will appear from the following description of the invention.

In the accompanying drawings:

Fig. 1 is a view in side elevation and partial cross section illustrating a hand telephone with the noise shield of the invention mounted thereon; and

Fig. 2 is a front elevational view, partly in cross section.

The noise shield of the invention generally includes a cup-shaped member adapted to fit about the face and means for flexibly supporting this member in various positions of angularity relative to the face of the user during speech.

Considering the structure shown in the drawings, numeral 2 denotes a frame member for a telephone handset. The frame is of tubular construction and its middle portion is provided with a conventional switch arrangement operated by means of a switch button 4, partly recessed in the frame member at the inner side thereof. Numeral 6 denotes an earphone at the upper end of the frame member, and numeral 8 denotes a base portion of the frame to which the noise shield body element 9 of the invention is attached. This body includes several integral instrumentalities for the application and functioning of the device, as will be more specifically described hereinafter.

The noise shield member is cup-shaped as shown in Fig. 1, having curved outer front edges for engaging against the face of a person and forwardly diverging side walls denoted by the numeral 16 and constituting part of a voice chamber 17. Preferably the noise shield member

2

is composed of moderately soft rubber or rubber-like material such as neoprene. Other suitable substances may be employed. At the lower or rear end of the body element 9, I have provided a cylindrical webbing or tube 22 which is an integral continuation of the side walls and has formed on the inner side thereof extending on to the right and left walls of the voice chamber 17 two longitudinal rib portions 20, through which are formed respective air passages 18. The cylindrical webbing 22, at its lower end, terminates in a hollow base or neck part 19 of reduced diameter, open rearwardly and having an integral interior terminal neck 21 of further reduced diameter, to permit its engagement and fit around an upper reduced part of the base 8 of the frame member. The base is terminally shaped and channeled circumferentially so as to receive the neck 21 as shown in the drawings, and so presents an outwardly projecting ridge 23 which is fitted within the neck 19 and against the forward side of the neck 21.

Numeral 14 indicates a biscuit shaped microphone which is snugly supported in a socket member 15, in turn integral and concentric with the tube 22 and suspended therewithin for moderate universal pivotal or translative movement of the socket relative to the base 8, in the manner more clearly indicated in Fig. 2 where a thin planiform annular wall 24 normal to the axis of the tube is the joining part. As will be observed from an inspection of this figure, the annular bottom or microphone seat 13 of the socket member 15 occurs in spaced relation with respect to the plan of a planiform bottom flexible annular planiform wall 26 formed on the rear end of the tube 22 and joining the latter to the neck 19 of the annular webbing 22, thus supporting the socket member in a highly-flexible manner so that movement of the upper portion of the noise shield, including the sidewalls, 16, together with the microphone 14, may occur relative to the base portion of the frame 8. Electrical conductors, 12, extending through a passageway, 10, in the frame, 8, project upwardly and are connected at the under side of the microphone, as shown in Fig. 1. These wires are adapted to move with the microphone and upper portion of the noise shield when displacement occurs.

It should be noted that the ribs and passages 18 extend a substantial distance forwardly beyond the socket member 15 and in use are located laterally of the mouth of the user. They vent excess air from within the shield member, so as to avoid interference with utterances of

the user by back pressure in the voice chamber, and they are small enough to attenuate sound passing therethrough so that voice sounds escaping will be faint. Their indirect relation to the path of sound originating in the larynx of the user will in addition result in great interference between, and damping of, sound waves gaining access thereto, so that no words uttered within the device will be distinguishable by a nearby person. Since the facial surfaces of the user which close the forward side of the voice chamber 11 are sound-absorbing, and since in-phase waves of original speech sounds gaining access to the vent passages 18 must be reversed in direction, principally by components of reflection from facial surfaces, out-of-phase echoes in the voice chamber which are immaterial in affecting message reception at the microphone 15 are of amplitude which is substantial in relation to that of in-phase sound waves reaching the passages 18, and so interference will contribute further to making escaping sound components of speech indistinguishable.

Due to the nature of the material of the body 9, the planiform wall 26 is extremely flexible so that the whole shield and microphone as a unit are easily rockable in any direction on the base 8, and the shield will consequently become automatically adjusted to various angular positions, according to the peculiarities of various faces or the mouth adjustments desired at different times by a user. In addition, there are permitted angular movements of the shield unit freely in relation to the base, incident to movements of the chin of a speaker using the device. It will be seen in Fig. 2 that the wall parts 16' at top and bottom of the mouthpiece or voice chamber are thinner than the wall parts 16 at the sides of the voice chamber.

This permits the user to articulate more freely, avoiding impedance of oral motions. While the lower wall part 16' will move principally, incident to ordinary mouth movements, depression of this part will produce a slight rocking of the shield and microphone downwardly as a unit, and the upper part 16' will flex slightly to permit and respond to such rocking without objectionably pressing vertically downwardly on the upper lip of the user.

The rocking of the unit as stated will result in always presenting the microphone toward the speaker in such position as to most efficiently respond to voice utterances—that is, in planes closely approximating the normal in relation to the mean directions of the voice waves at various positions of the mouth relative to the base 8.

At the same time, throughout all positions of the shield device relative to the base frame 8, the microphone is floatingly supported by the web or wall 24, so that it is in some measure translatively movable by its inertia within the tube 22 when the shield is subjected to concussions or blows. The air space surrounding the socket 15 within the tube 22 will reduce the force of impact of shock waves from explosions.

It will thus be seen that the noise shield is so designed that it may be used by individuals having unusual variations in facial size and contour. Moreover, it is so flexibly mounted with respect to the base of the frame that it yields readily to facial motions required in speech articulation. These two features combine to make the device extremely comfortable and exceedingly efficient. The air passages, 18, permit the breath to escape while speaking. These openings are

designed as to have a minimum effect on the acoustic insulation provided by the noise shield.

It is intended that the flexible mounting of a microphone relative to a supporting base may be carried out with other forms of supporting structures than the particular flexible webbing described. Similarly, it is intended that the arrangement of a ductile mounting for a microphone may be combined with other types of supporting members.

While I have shown a preferred embodiment of my invention, it should be understood that various changes and modifications may be resorted to, in keeping with the spirit of the invention as defined by the appended claims.

Having thus described my invention, what I claim is:

1. As an article of manufacture, a noise shield member for a telephone handset comprising a cup-shaped member of resilient material shaped and adapted to conform forwardly to the face contours of the user, means at the rear part of the cup-shaped member for connecting this member to the base of a rigid handset frame, said means comprising a resilient integral tube, a flexible inward extension from said tube at a forward part thereof, and an integral forwardly open microphone-receiving socket member on said inward extension constructed to fit around a microphone unit, said socket member in spaced relation to said tube and to said means for connecting said cup-shaped member to the said base and having an integral annular microphone seat at its rear part.
2. An integral combined noise shield, and shock absorbing mount for microphones in telephone sets, comprising a body of elastic highly flexible material having a hollow base neck open at the rear part of the body constructed to elastically receive and bind upon an inserted base frame member; said body having a planiform flexible wall extending outward from said neck normal to the axis of the neck, and having an integral cylindrical coaxial tube extending forwardly therefrom, flared at its forward portions to form a voice chamber and mouth-piece generally conforming to contours of the face of a person, a second planiform cylindrical wall spaced forwardly from the first-named planiform wall formed integrally within the said tube, a microphone transmitter socket formed integrally on the inner edge of the last-named wall in spaced relation to said tube, shaped to fit around a conventional transmitter unit and being open to said voice chamber and having a bottom seat spaced rearwardly from said voice chamber so as to support an engaged transmitter unit in spaced rockable relation to an engaged base.
3. A sound shield and shock absorbing mount for microphones in telephone sets, comprising a body of elastic highly flexible material having a voice chamber open to receive therein and conform to a portion of the face of the user, a microphone socket integral with said body constructed to elastically fit around and support a microphone and having an integral lateral annular substantially planiform wall normal to the axis of the socket spaced within and joined to a rearward part of said body whereby to support a microphone in the socket yielding for universal movement relative to the other parts of said body, said body having a tubular highly flexible part extended rearwardly around and in spaced relation to said socket, shaped for securing engagement with a support whereby said tubular

part constitutes a spaced protective wall spaced around the socket and a universal pivot coupling between the support and the parts of said body forwardly of the support.

4. The structure of claim 3 wherein the wall of the voice chamber is extended continuously rearward in the form of a non resonant highly flexible elastic tube shaped and constructed at its rear extremity to fit snugly around a support to secure the device on such support and seal the rearward end of the tube, said lateral annular wall continuously circumscribing said socket and continuously joined to said tube whereby with the seal at the support and the fit of the socket upon a microphone, an enclosed air space is formed surrounding the microphone at the sides and rear.

5. The structure of claim 3 wherein the rearward end portion of said tubular part is formed with a thin-walled neck, and a thickened second farther neck of further restricted diameter, and

a handset member including a base having a part to fit snugly in the neck and having a channel part to snugly receive the said second neck.
